(57) **CLAIM**

The ornamental design for buckle with bottle opener, as shown and described.

DESCRIPTION

FIG. 1 is a front side elevation view of my new design for a buckle with bottle opener, the bottle opening lever is shown in broken lines and is for illustrative purpose only and forms no part of the claimed design.

FIG. 2 is a back side elevation view of FIG. 1.

FIG. 3 is a left side elevation view of FIG. 1, the right side elevation view being a mirror image thereof.

FIG. 4 is a top side plan view of FIG. 1.

FIG. 5 is a bottom side plan view of FIG. 1; and, FIG. 6 is a front perspective view of FIG. 1.
